assigns to

Wager and Gates, of same place.

Letters Patent No. 1898-Dated Jan. 26, 1893

Design for Stove Plates.

The schedule referred to in these Letters Patent and making part of the same.

To all whom it may concern:

Be it known that we Nicholas S. Wedder, and Benjamin A. Johnson, each of the City of Troy, in the County of Rensselaer and State of New York, have jointly invented or produced a new and original ornamental Design for Stove Plates, and we do hereby declare that the following is a full and exact description thereof, reference being had to the annexed photograph of a side of a cooking stove having our said ornamental design.

This ornamental design consists of two hinge-straps a, a, rivet-heads b, b, b, a strap like rectangular frame c, c, c, with mitre joints d, d, a border moulding e, and a panel f, on a large oven door. G: two long hinge straps h, h, two connecting straps i, i, mitre joints j, j, rivet heads k, k, k, k, a border moulding l, and a panel m, on a small oven door N, and a long hinge strap o, a short one p, two connecting straps q, q, a base moulding r, shown in section in figure 2, a border moulding s, rivet heads t, t, t, t, and a panel u, on a fire-door V, all so shaped and arranged as to present the appearance shown by the annexed photograph.

What we claim as new and of our invention or production and desire to secure by Letters Patent is -

The above described ornamental design of the cast iron doors or plates, G. N. V. of a cooking stove.
